MOLD FOR SHOE COUNTERS

Leo F. Exley, Johnson City, N. Y., assignor to
Endicott Johnson Corporation, Endicott, N. Y.,
a corporation of New York

Application April 29, 1937, Serial No. 139,802

10. Claims. (Cl. 12—66)

This invention is a novel female mold particularly adapted for shaping counter-stiffeners for boots and shoes, same comprising a pair of opposed recessed jaws hingedly connected together, practical embodiment thereof to enable others familiar with the art to adopt and use the same; the recesses of the jaws being adapted to embrace parts, for which protection is desired.

Fig. 1 is a front elevation of the usual form of back of a stiffener blank inserted therein, means of shaping therebetween the upper side walls and the recesses of the jaws being provided at the opposed faces of the jaws and showing in dotted lines the bent stiffener blank entering the straight-line crevice at the rear of the inner ends of the recesses for retaining the bent heel portion of the stiffener blank confined within the recesses, thereby preventing the bent end from being pinched in the mold between said opposed faces of the jaws adjacent the pivot when the jaws are swung into closed position.

Fig. 2 is an end elevation of the mold shown in Fig. 1 illustrating the usual straight-line crevice between said opposed faces of the jaws adjacent the pivot when the jaws are swung into closed position.

Fig. 3 is a perspective view of the usual counter-stiffener blank showing the sharp bend thereof prior to placing same in the mold; and showing the mold between said opposed faces of the jaws adjacent the pivot when the jaws are swung into closed position.

Fig. 4 is a front elevation of my novel female mold showing the jaws in open position, and the mold receiving therebetween the counter-stiffener blank, the mold showing the location of my overlapping inter-recess. When released within the mold the opposed serrated surfaces at the crevice which receive the blank spring outwardly against the walls of the recesses and hold the blank in place in the mold while the two jaws are being moved toward each other to closely embrace the blank. Fig. 5 is an end elevation of my novel mold receiving therebetween the counter-stiffener blank shown in Fig. 4 with the jaws swung into closed position of the blank, which constitutes the top of a flange.

Fig. 6 is an end elevation of my novel mold would enter the crevice of the mold in rear of the blank shown in Fig. 4, showing the sinuous crevice formed between the opposed faces of the blank when the jaws adjacent the pivot, causing said portion of the blank to be pinched or crushed by dis-

placement of the fibres of the blank.

The primary object of my invention is to obviate this objection by providing female mold now in common use, as comprising jaws in which the opposed surfaces thereof at the crevice in rear of the recesses are serrated so as to continuously overlap and interlock, whereby when the mold is open the slightly separated jaws are pivoted on a pintle 3 and movable towards or away from each other in the usual manner during the operation of the machine by means of links 4 and 5 connected with slide 6. Pintle 3 is housed in semi-circular recesses 1b, 2b, respectively, in the blank during the molding operations, the surfaces of the blank from entering between the opposed surfaces during the molding operations, the crevices formed by said overlapping interlocking serrations presenting a substantially sinuous curve. Usually the surfaces 1c, 2c of the jaws between the recesses 1a, 2a and pintle 3 are plane surfaces of relatively great amplitude supplanting the usual straight crevice which is present in the jaws of the usual female mold, the teeth of the serrations in the surfaces 1c, 2c converging towards pintle 3 when my jaws never passing entirely out of their corresponding roots even when the jaws are in opened position.

I will explain the invention with reference to the accompanying drawing which illustrates one

The counter-stiffener blank B is usually formed of leather or fibre cut to desired shape, and the operator bends it into the general horse-shoe shape (Fig. 3) prior to insertion of the blank in the recess 1a, 2a, which operation usually results in a sharp bend B' at the center of the blank; and this portion B' often enters into the V-shaped crevice 1c, 2c, of the open mold so that the subsequent closing of the jaws drags into the crevice 10 and traps therein a part of the bent portion B' of the blank which will be thus pinched or injured causing the formation of a ridge along the bend of the finished blank, which ridge not only detracts from the appearance and sale of the 15 counter, but is a potential source of weakness in that the ridge is actually formed of fibres of the blank which have been dislodged from their normal place in the blank, removing their anchorage, the dislodged fibres being crushed and 20 broken by the molds in the act of closing. This ridge is actually a rupture extending from the top to bottom of the finished counter at the center of the heel, and often causes the counter-stiffener to break at this point.

25 My novel female mold shown in Figs. 4-7 obviates this objection by replacing the usual straight-line crevice formed by surfaces 1c, 2c, in Figs. 1-2 with a series of interlocking serrations formed on the opposed faces of the jaws extending from the inner ends of the recesses 1a, 2a to the inner or pintle ends of the jaws, said serrations being in the form of ridges 1x, 2x and grooves 1y, 2y as shown in Figs. 5-7 inclusive, the ridges on one jaw interlocking in the grooves 35 in the opposite jaw, and the ridges and grooves being of sufficient length and depth that when the jaws are opened to receive the blank B the ridges will not be entirely withdrawn from their cooperating grooves but will form a substantially 40 sinuous crevice at the inner ends of the recesses 1a-2a of substantial amplitude, thereby positively preventing the bent end B' of the blank from entering said crevice.

These ridges 1x, 2x may be one or more in 45 number, and may also be of angular cross-section, or may be rounded convolutions as shown in Figs. 5-7 inclusive, or may be of any other desired cross-section which would make the serrations of the jaws interlocking. As the ridges 50 1x, 2x in one jaw interlock into corresponding grooves 2y, 1y in the opposite jaw the ridges of both jaws cross the axis of the pintle 3 and thus make an interlocking fit into recesses in the opposite jaws, thereby dispensing with the 55 straight-line crevice between surfaces 1c, 2c, shown in Figs. 1-2, and forming an effective barrier preventing any portion of the blank B from passing beyond the confines of the mold cavity 1a-2a. Therefore no unwarranted 60 placement or distortion of the fibers of the blank B can be effected at any point in the mold.

Moreover in the usual mold construction shown in Figs. 1-2 the two jaws are kept in lateral adjustment only by the pintle 3 with respect to 65 the flange B2 (Fig. 3) formed by the usual slide (not shown) which passes over the face of the mold, whereas in my construction the interlocking serrations not only permit movement of the mold jaws toward and away from each other, but same also hold the jaws in proper lateral adjustment so that the slide of the machine which 70 forms the flange B2 (Fig. 3) around the lower edge of the finished stiffener will always form flanges of unvarying and uniform thickness, 75 which is a very desirable result.

I claim:—

1. A mold for shaping counter-stiffener blanks comprising a pair of opposed recessed jaws movable towards or from each other and provided with portions adapted to prevent a blank being caught in the crevice between the jaws during the shaping operation; the said portions maintaining the lateral adjustment of the jaws when closed. 5

2. A mold for shaping counter-stiffener blanks 10 comprising a pair of opposed recessed jaws movable towards or from each other and provided at the rear ends of the recesses with overlapping and interlocking portions which when the mold is opened will prevent a blank being pinched during the shaping operation. 15

3. A female mold for shaping counter-stiffener blanks or the like comprising a pair of opposed recessed jaws movable towards or from each other, the opposed faces of the jaws adjacent 20 the recesses being provided with overlapping and interlocking portions adapted to prevent the blank from entering the crevice between the opposed faces of the jaws during all shaping operations. 25

4. A mold for shaping counter-stiffener blanks comprising a pair of opposed recessed jaws movable towards or from each other, the opposed faces of the jaws adjacent the recesses being provided with overlapping portions forming a 30 substantially sinuous crevice between the inner ends of the recesses in the jaws when the mold is open, and preventing the blank being pinched during the shaping operations. 35

5. A female mold for shaping counter-stiffener 40 blanks or the like comprising a pair of opposed recessed jaws movable towards or from each other, the opposed faces of the jaws adjacent the recesses being provided with interlocking overlapping portions forming a substantially sinuous crevice of substantial amplitude between the opposed faces of the jaws when the mold is open, thereby retaining the blank within the confines of the recesses. 45

6. A mold for shaping counter-stiffener blanks 4 or the like comprising a pair of opposed recessed jaws movable towards or from each other, the opposed faces of the jaws beyond the inner ends of recesses being provided with alternating ridges and grooves interengaging when the mold is 5 opened to prevent pinching of a blank entered between the jaws preparatory to shaping same. 5

7. A female mold for shaping counter-stiffener blanks or the like comprising a pair of opposed recessed jaws movable towards or from each other, the opposed faces of the jaws beyond the inner ends of recesses being provided with alternating ridges and grooves interlocking while the mold is opened to form a substantially sinuous crevice of substantial amplitude between the opposed faces of the jaws retaining the blank within the confines of the recesses. 60

8. In a mold as set forth in claim 7, the interlocking ridges and grooves maintaining the jaws in fixed lateral adjustment when the jaws are closed. 65

9. A mold for shaping counter-stiffener blanks or the like comprising a pair of pivoted recessed jaws, the jaws being provided adjacent their pivot with interengaging and interlocking projections which when the mold is opened will prevent a blank being pinched between the jaws at the inner ends of the recesses during the shaping operation. 70

10. A female mold for shaping counter-

stiffener blanks or the like comprising a pair of opposed recessed jaws movable towards or from each other, the opposed faces of the jaws beyond the inner ends of recesses being provided with 5 interlocking serrations in the form of alternating teeth and grooves, the teeth of one jaw fitting within and terminating within the grooves

of the other jaw when the mold is opened thereby forming a substantially sinuous crevice of substantial amplitude at the inner ends of the recesses retaining the blank within the confines of the recesses during the shaping operations. 5
